UNITED STATES PATENT OFFICE

FREDERICK NEWTON REYNOLDS, OF AMARILLO, TEXAS

DESIGN FOR A CHECK HOLDER

Application filed March 10, 1930. Serial No. 34,799. Term of patent 3½ years.

To all whom it may concern:

Be it known that I, FREDERICK N. REYNOLDS, a citizen of the United States, residing at Amarillo, in the county of Potter and State of Texas, have invented a new, original, and ornamental Design for a Check Holder, of which the following is a specification, reference being had to the accompanying drawing, forming part thereof.

I claim:

The ornamental design for a check holder, as shown.

FREDERICK NEWTON REYNOLDS.
